UNITED STATES PATENT OFFICE.

HARRY WILSON PARKER, OF BROOKLYN, NEW YORK.

HYDROCARBON BURNER.

Application filed May 27, 1924. Serial No. 716,158.

To all whom it may concern:

Be it known that I, HARRY WILSON PARKER, a citizen of the United States, and resident of Brooklyn, in the county of Kings and State of New York, have invented a certain new and useful Hydrocarbon Burner, of which the following is a specification, the same being a full, clear, and exact description of the invention, its structure, and 10 operation.

This invention relates to devices for producing heat by means of liquid fuel, and particularly to burners of that character in which a jet of air or steam, or both, is employed carrying with it a spray of coal oil or petroleum which is lighted and burned.

The principal object of the invention is to make a pressure blue flame fire of as near perfect combustion as possible.

Another object of the invention is to convert all of the oil into a combustible gas when properly mixed with steam without the carbonization of any of the same.

Another object of the invention is to provide means whereby the gas supply to said fire will be fixed, certain, unchangeable and constant by a heat insulated source of oil supply.

A further object of the invention is to provide means to ignite all of the particles of gas that are generated without allowing them to escape by drafts of air.

Another object of the invention is to supply air to the burner in such a diffused manner that such a proper mixture of the gas oil and steam therewith is made as to ensure practically perfect combustion.

Another object of the invention is to provide a safe, economical and positive pressure blue flame burner.

Another object of the invention is to employ such a manner of construction that convenience of manufacture and of repairs is secured.

A still further object of the invention is to provide a pressure blue flame burner that shall be of simple construction, inexpensive to manufacture and efficient and durable in practical operation.

With the above named objects of the invention, and other objects and purposes which will be described below, in view, the invention consists in the construction, arrangement, combination and operation of parts hereinafter set forth.

In the drawings, illustrative of one embodiment of the invention, which accompany and form a part of this specification,

Figure 1 represents a section taken on the line I—I Figure 2;

Figure 2 is a section on the line II—II Figure 4;

Figure 3 is an elevation of the valve proper, partly in section;

Figure 4 is a plan view partly broken away;

Figure 5 is a view in section of the valve; and

Figure 6 is a section on the line VI—VI Figure 3.

Referring more in detail to the drawings, the numeral 1 denotes the steam inlet (shown more clearly in Figure 2) leading to the wet steam chamber 3 communicating with the steam superheating chamber 4 by the nipple 43; and 2 the final outlet of the superheated steam from the chamber 4 to convey the same to the channel 5 of the steam nozzle 6. The outlet or nipple extends from the annular superheating chamber 4 of the casting 27 into which chamber the steam flows after having passed through the annular wet steam chamber 3 of the casting 28 communicating as stated with the inlet 1. The chambers 3 and 4 are respectively formed in the two sections 27 and 28 of a hollow wall which sections are rigidly attached together.

The steam nozzle 6 and oil valve 14 are held in the casting 24 and are formed with a longitudinal channel in which is located a casing 15 tapered at its inner end, the other extremity terminating in a hexagonal nut 15'. The casing 15 is screwed to a housing 20 at the inner end of which is a flange 20' having orifices 21. The housing 20 has a channel 9 which communicates with the oil inlet 8. In the said housing works an adjustable rod 10 provided at its outer end with a radio dial 46 for convenience in adjustment and being screwed into the said housing.

The rod 10 has a longitudinal bore 11 and a transverse bore 12 communicating with the same and with the channel 9 of housing 20, and also another transverse bore 13 communicating with the bore 11 and with the interior chamber of the casing 15. The inner end of the bore 11 is closed by a needle valve 14 the conical end of which enters the taper-

ing mouth or valve seat of the casing 15. A washer 16 encloses the end of the needle valve and is held in position by a surrounding hexagonal nut 17 screwed to the casing 15 and having an orifice larger than the port or seat of the oil valve 14.

A metallic and preferably copper envelope or casing 18 is held by the nut 17 snugly against the casing 15, which envelope encloses a heat insulating material 19, as magnesia, to keep the oil supply cool. At the inner end of the copper envelope 18 and surrounding the same is a tapering steam nozzle 6 seated in the casting 24 and having slots 15 or orifices 7 which are not only made tapering but also have a tangential slant, which orifices communicate with the interior annular channel 5 passing around the nozzle 6 and connected with the outlet nipple 2. 20 Packing 45 is preferably used to seal the inner end of the steam nozzle 6.

In order to prevent an undue amount of heat generated by the burner from creeping back to the source of oil supply I reduce the 25 metal adjacent to the oil supply by making the orifices 21 of the flange 20' as large as the stability of the structure will permit and insert an asbestos ring 22 between the cap 23 and the casting 24 to which it is attached 30 to snugly hold the various parts of the nozzles together in operative position. The said cap 23 is also formed with a large central opening 23' and the casting 24 is also made with orifices 25, all of the said openings 35 serving to reduce the metal and thereby keep the metal parts near the oil supply as cool as possible under working conditions. The nozzles comprising the oil valve and steam nozzle are placed at one side of the 40 mixing chamber 47 and the air passage 40.

The hollow castings 27, 28 and 24 are held together by stud bolts 30, the castings 27 and 28 having between the same a heat insulating ring 29. A conical or dome shaped 45 casting or distributor 33 is screwed on the upwardly extending and contracted goose neck wall of the channel ascending from the mixing chamber 47 of the casting 24. At the said joint is screwed a tapered tube 34 forming between the latter and the casing 33 an intermediate chamber 35. A gas outlet from the chamber 35 is formed by the orifices 36 50 in the lower part of the wall of the latter.

In the annular combustion chamber 41 55 formed by the castings 27 and 28 I locate a perforated screen or baffle in order to diffuse and distribute air from the lower open portion or air passage 40 of the casting 28 to the base of the combustion chamber 41 formed 60 by the said baffle. I prefer to use a plurality of screens of different mesh, as the screens 37, 38, 39, the orifices in the same being each of increased diameter from the ones below the same or of progressively larger mesh 65 from the lowest to the highest, in order to

thoroughly diffuse the air in adequate volume yet sluggishly to the whole base of combustion. The grate is held in an air tight relation and the junction between the grate and the burner is also air tight, the grate 70 line being indicated by the numeral 42.

A partition 44 is formed in the chamber 4 and a partition 49, straddling the goose neck, is set up in the chamber 3. I also prefer to provide at least one compartment 48 75 between the castings 24 and 28 to contain heat insulating material. The numeral 26 represents my emergency drain for the chamber 27.

The steam from the inlet 1 first enters 80 the wet steam chamber 3 and from there, on account of the partition 49 in the same, is forced to pass into the superheating chamber 4, and thence, by reason of the partition 44 therein, it is led through nipple 2 and channel 5 formed between the steam nozzle 6 and the outlet 2 to the spraying orifices 7, the walls of the chambers 3 and 4 serving to enclose the combustion chamber and, together with the chambers 3 and 4 containing 90 flexible devices to form a plurality of channels, to divide the fluids passing through the same, as the wires 32 which may be entered through orifices as 31.

The oil enters the mixing chamber 47 from 95 the needle valve in a stream or jet of suitable small size, where it is met by the various superheated currents emanating from the orifices 7 of the nozzle 6. On account of the tapered position of the said orifices the steam currents will converge, and by reason of the tangential inclination of the said orifices the said steam currents will also have a rotary movement. On account of this double movement of the steam sprays the 105 oil will become thoroughly mixed with the same and gasified in the mixing chamber thence passing to the distributor 33.

By the means described the oil is kept so cool as to prevent any carbonization of the 110 same to clog the valve, thereby ensuring a long life to the efficiency of the burner. The oil valve comprises a needle valve seated in the steel shell or casing 15 and adapted to be removed without taking the apparatus 115 apart.

The gas comprising the commingled oil, 120 gas and steam passes from the mixing chamber up into the tube 34 of the superheating gas chamber 35 and escapes through the orifices 36 into the base of the combustion chamber. Here the superheated gas is met by the air currents or streams entering through the practically unobstructed air passage 40 and thence rising from the perforated screens in such adequate quantity and sluggishness of movement as to cause all of the minute particles of oil gas to be burned under adequate pressure with an intense blue flame without the creating of any 125 130

deposits of carbon whatsoever. The burner may be lighted by any suitable or desired means such as are in common use.

I wish it to be understood that I do not desire to limit myself to the particular use or the exact details of construction shown and described, for obvious modifications will occur to persons skilled in the art.

What I claim as my invention is:—

- 10 1. In a hydrocarbon burner, a combustion chamber, a hollow wall forming a wet steam chamber and a steam superheating chamber thereabove, an air passage of substantially the same diameter as said combustion chamber therebelow, a centrally located means to supply superheated gas to the base of the combustion chamber, a large mixing chamber having a passage leading to the said supply means and extended laterally from said passage, and oil and steam nozzles communicating with the said mixing chamber, the said nozzles being located at the extended side of the mixing chamber.
- 15 2. In a hydrocarbon burner, a combustion chamber, a sectional hollow wall, one section forming a wet steam chamber and the other section a steam superheating chamber thereabove, the two sections of said hollow wall being rigidly attached together, an air passage of substantially the same diameter as said combustion chamber below the latter, a centrally located means to supply superheated gas to the base of the combustion chamber, a large mixing chamber having a passage leading to the said supply means and extended laterally from said passage, and oil and steam nozzles communicating with the said mixing chamber, the said nozzles being located at the extended side of the mixing chamber.
- 20 3. In a hydrocarbon burner, a combustion chamber, a hollow wall forming a wet steam chamber and a steam superheating chamber thereabove, an air passage of substantially the same diameter as said combustion chamber therebelow, a centrally located means to supply superheated gas to the base of the combustion chamber, a large mixing chamber having a passage leading to the said supply means and extended laterally from said passage, and oil and steam nozzles communicating with the said mixing chamber, the said nozzles being located at the extended side of the mixing chamber.

- 25 4. In a hydrocarbon burner, a combustion chamber, a hollow wall forming a wet steam chamber and a steam superheating chamber thereabove, an air passage of substantially the same diameter as said combustion chamber therebelow, a centrally located means to supply superheated gas to the base of the combustion chamber, a large mixing chamber having a passage leading to the said supply means and extended laterally from said passage, and oil and steam nozzles communicating with the said mixing chamber, the said nozzles being located at the extended side of the mixing chamber and comprising a central oil outlet and a surrounding plurality of steam outlets tangentially disposed whereby the oil and steam are mixed with a rotary motion as they enter the mixing chamber.
- 30 5. In a hydrocarbon burner, a combustion chamber, a hollow wall forming a wet steam chamber and a steam superheating chamber thereabove, an air passage of substantially the same diameter as said combustion chamber therebelow, a centrally located means to supply superheated gas to the base of the combustion chamber, a large mixing chamber having a passage leading to the said supply means and extended laterally from said passage, and oil and steam nozzles communicating with the said mixing chamber, the said nozzles being located at the extended side of the mixing chamber and comprising a central oil outlet and a surrounding plurality of steam outlets tangentially disposed whereby the oil and steam are mixed with a rotary motion as they enter the mixing chamber.
- 35 6. In a hydrocarbon burner, a combustion chamber, a hollow wall forming a wet steam chamber and a steam superheating chamber thereabove, an air passage of substantially the same diameter as said combustion chamber therebelow, a centrally located means to supply superheated gas to the base of the combustion chamber, a large mixing chamber having a passage leading to the said supply means and extended laterally from said passage, and oil and steam nozzles communicating with the said mixing chamber, the said nozzles being located at the extended side of the mixing chamber and comprising a central oil outlet and a surrounding plurality of steam outlets tangentially disposed whereby the oil and steam are mixed with a rotary motion as they enter the mixing chamber.
- 40 7. In a hydrocarbon burner, a combustion chamber, a hollow wall forming a wet steam chamber and a steam superheating chamber thereabove, an air passage of substantially the same diameter as said combustion chamber therebelow, a centrally located means to supply superheated gas to the base of the combustion chamber, a large mixing chamber having a passage leading to the said supply means and extended laterally from said passage, and oil and steam nozzles communicating with the said mixing chamber, the said nozzles being located at the extended side of the mixing chamber and comprising a central oil outlet and a surrounding plurality of steam outlets tangentially disposed whereby the oil and steam are mixed with a rotary motion as they enter the mixing chamber.
- 45 8. In a hydrocarbon burner, a combustion chamber, a hollow wall forming a wet steam chamber and a steam superheating chamber thereabove, an air passage of substantially the same diameter as said combustion chamber therebelow, a centrally located means to supply superheated gas to the base of the combustion chamber, a large mixing chamber having a passage leading to the said supply means and extended laterally from said passage, and oil and steam nozzles communicating with the said mixing chamber, the said nozzles being located at the extended side of the mixing chamber and comprising a central oil outlet and a surrounding plurality of steam outlets tangentially disposed whereby the oil and steam are mixed with a rotary motion as they enter the mixing chamber.
- 50 9. In a hydrocarbon burner, a combustion chamber, a hollow wall forming a wet steam chamber and a steam superheating chamber thereabove, an air passage of substantially the same diameter as said combustion chamber therebelow, a centrally located means to supply superheated gas to the base of the combustion chamber, a large mixing chamber having a passage leading to the said supply means and extended laterally from said passage, and oil and steam nozzles communicating with the said mixing chamber, the said nozzles being located at the extended side of the mixing chamber and comprising a central oil outlet and a surrounding plurality of steam outlets tangentially disposed whereby the oil and steam are mixed with a rotary motion as they enter the mixing chamber.

municating with the said mixing chamber, the said nozzles being located at the extended side of the mixing chamber, an oil supply and a steam supply and means to keep the oil supply cool by reducing the thickness of the metal surrounding the same.

4. In a hydrocarbon burner, a combustion chamber, a hollow wall forming a wet steam chamber and a steam superheating chamber thereabove, an air passage of substantially the same diameter as said combustion chamber therebelow, a plurality of screens between said air passage and said combustion chamber, said screens being of progressively larger mesh from the lowest to the highest, a centrally located means to supply superheated gas to the base of the combustion chamber, a large mixing chamber having a passage leading to said supply means and extended laterally from said passage, and oil and steam nozzles communicating with the said mixing chamber, the said nozzles being located at the extended side of the mixing chamber, an oil supply and a steam supply, and means to keep the oil supply cool by insulating material surrounding the same.

5. In a hydrocarbon burner, a combustion chamber, a hollow wall forming a wet steam chamber and a steam superheating chamber thereabove, an air passage of substantially the same diameter as said combustion chamber therebelow, a centrally located means to supply superheated gas to the base of the combustion chamber, a large mixing chamber having a passage leading to the said supply means and extended laterally from said passage, and oil and steam nozzles communicating with the said mixing chamber, the said nozzles being located at the extended side of the mixing chamber and comprising a central oil outlet and a surrounding plurality of steam outlets tangentially disposed whereby the oil and steam are mixed with a rotary motion as they enter the mixing chamber.

Signed at New York, in the county of New York and State of New York, this 20th day of May, A. D. 1924.

HARRY WILSON PARKER.
